Primary Examiner — W. A. Teddy Falloway*Assistant Examiner* — Sarah J Ault(74) *Attorney, Agent, or Firm* — Perkins Coie LLP(57) **CLAIM**

The ornamental design for jewelry, as shown and described.

DESCRIPTION

FIG. 1 is an isometric view of jewelry showing my new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines in the drawings are for the purpose of illustrating portions of the jewelry that form no part of the claimed design.
